US00D805891S

(12) **United States Design Patent** (10) **Patent No.:** **US D805,891 S**
(45) **Date of Patent:** **** Dec. 26, 2017**

(54) **PACKAGE**

- (71) Applicant: **Lutron Electronics Co., Inc.**,
Coopersburg, PA (US)
- (72) Inventors: **Benjamin F. Bard**, Zionsville, PA
(US); **David S. Bennett**, Bethlehem, PA
(US); **Jason C. Killo**, Emmaus, PA
(US)
- (73) Assignee: **Lutron Electronics Co., Inc.**,
Coopersburg, PA (US)
- (**) Term: **15 Years**
- (21) Appl. No.: **29/591,331**
- (22) Filed: **Jan. 19, 2017**

Related U.S. Application Data

- (63) Continuation of application No. 29/544,145, filed on Oct. 30, 2015, now Pat. No. Des. 780,570.
- (51) **LOC (10) Cl.** **09-03**
- (52) **U.S. Cl.**

(57) **CLAIM**

The ornamental design for a package, as shown and described.

DESCRIPTION

FIG. 1 is a front perspective view of a package showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is another perspective view of the package shown in an alternate configuration.

The broken lines illustrate structure or features which form no part of the claimed design.

The diagonal parallel shading lines represent a transparent surface.

1 Claim, 6 Drawing Sheets
